UNITED STATES PATENT OFFICE.

JOSEPH KINTZ, OF BALLARD VALE, MASSACHUSETTS, ASSIGNOR OF ONE-HALF TO THE CRAIGHEAD & KINTZ COMPANY, OF NEW YORK, N. Y.

ELECTRIC-LIGHT FIXTURE.

SPECIFICATION forming part of Letters Patent No. 447,832, dated March 10, 1891.

Application filed May 15, 1890. Serial No. 351,868. (No model.)

To all whom it may concern:

Be it known that I, JOSEPH KINTZ, of Ballard Vale, in the county of Essex and State of Massachusetts, have invented a certain new and useful Improvement in Electric-Light Fixtures, of which the following is a specification.

I will describe a fixture embodying my improvement, and then point out the novel features in the claims.

In the accompanying drawings, Figure 1 is a central longitudinal section of an electric-light fixture embodying my improvement. Fig. 2 is an end view of the main part or upper section. Fig. 3 is an end view of an arm or secondary part. Fig. 4 is a bottom view of the two parts or sections detached.

Similar letters of reference designate corresponding parts in all the figures.

20 A designates the main part or upper section. It consists of a plate *a*, having a forwardly-extending hollow projection *a'* and a nipple or socket *a²* projecting from the latter. This part may be secured in any suitable 25 manner to a wall or any other support—as, for instance, by screws passing through holes *a³* in the plate *a*. The projection *a'* is shown as of rectangular form and as cast integral with the plate *a*. The nipple or socket *a²* may be made separately and provided with 30 a shank having an external screw-thread and fitting in and engaging a tapped hole in the forward part of the projection *a'*. In the back of the nipple or socket *a²* a block *a⁴*, of wood or like material, is inserted. Preferably 35 it will be driven tightly into place, or it may be secured in position in any desirable manner. A pin *a⁵*, extending longitudinally into the nipple or socket and block, acts as a key, 40 preventing the rotation of the block independently of the nipple or socket.

a⁶ a⁷ designate two electrodes extending longitudinally through the block *a⁴*. As here shown, these electrodes consist of wires driven 45 into the block side by side, and having at the rear end eyes, with which wires *a⁸ a⁹*, forming part of an electric circuit, are connected. At the front end these electrodes project slightly beyond the block.

50 B designates an arm or secondary section of the electric fixture. It is made in the form

of a tube constructed at one end to fit the nipple or socket *a²* and provided at the other end with a nipple *b*, to which an electric lamp may be fastened. The end which enters the 55 nipple or socket *a²* is provided with a block *b'*, of wood or like material. Preferably this will be driven into place. As shown, it has a notched flange-like portion projecting beyond the main portion of the part or section 60 B. The part or section B has, however, a lug *b²*, which extends into a notch in the flange-like portion of the block, interlocking therewith, so as to prevent any rotary movement 65 of the block. Electrodes *b³ b⁴* are inserted in the block *b'* in positions corresponding to the electrodes *a⁶ a⁷*. They may be made like the electrodes *a⁶ a⁷* and inserted to project slightly beyond the protruding end of the block. Wires *a¹¹ a¹²* may be engaged with them and 70 extended through the part B to its nipple *b* for connection with a lamp.

Around the part B, near the end which engages with the socket, is a circumferential rib *b⁵*, which may be formed upon or attached to 75 the part in any suitable manner. When the end of the part B is inserted in the nipple or socket, this rib will be close to the outer extremity of the nipple or socket. The electrodes *b³ b⁴* will then bear against the electrodes *a⁶ a⁷*. The part B is also provided with a longitudinal rib *b⁶*. This will project into a notch *a¹⁰*, with which the nipple or socket is provided, and will thereby preclude any 80 rotary movement of the part B relatively to 85 the part A.

C designates a coupling-piece, consisting of a ring surrounding the part B forward of its rib *b⁵* and having an internally-screw-threaded flange which will extend over the 90 said rib and engage with the externally-screw-threaded forward outer end of the nipple or socket *b²*.

When the two parts A and B are fitted together, the rib *b⁶* will interlock with the notch *a¹⁰* and insure a proper meeting of the two 95 pairs of electrodes, and the coupling-piece will maintain an efficient contact between them. The projection of the electrodes *b³ b⁴* will be such that when the coupling-piece is 100 engaged these electrodes will be forced into contact with the electrodes *a⁶ a⁷* before the

circumferential rib b^5 on the part B will reach the opposite end of the nipple or socket a^2 , and also before the extremity of the longitudinal rib b^6 can reach the bottom or inner 5 end or the notch a^{10} in the nipple or coupling-piece.

By my improvement I produce a very simple electric fixture which may readily have its sections separated and reunited in proper relation.

What I claim as my invention, and desire to secure by Letters Patent, is—

1. In an electric fixture, the combination of a main part or section provided with a nipple, a plug inserted in the back part of the nipple, electrodes fitted in said plug and protruding from the forward end of the plug, a secondary part or section made in the form of a tube, a plug fitting in the inner end of 15 said secondary part and having a flange-like portion lapping over said end of the secondary part and a notch in said flange, a rib or 20

tongue on the secondary part entering the notch of the flange, electrodes in the last said plug, and a coupling-piece connected with the one part and engaging with the other, substantially as specified.

2. In an electric fixture, the combination of a main part or section composed of a plate-like portion having a hollow forward or outward projection and a nipple inserted in said projection and constructed so as to be open at both ends, a plug inserted at the back end of said nipple, electrodes arranged in said plug, a secondary part or section made in the form of a tube of a size to enter the outer end of the nipple, a plug in said secondary section, electrodes in said plug, and a coupling-piece connected with the one part and engaging with the other, substantially as specified. 35 40

JOSEPH KINTZ.
